UNITED STATES PATENT OFFICE.

IRA C. CLARK, OF ST. LOUIS, MISSOURI, ASSIGNOR TO HIMSELF AND JOSEPH L. SCHULER, OF ST. LOUIS, MISSOURI, A PARTNERSHIP DOING BUSINESS AS THE SCHULER & CLARK MANUFACTURING CO.

APPAREL-ATTACHED PIPE.

SPECIFICATION forming part of Letters Patent No. 761,148, dated May 31, 1904.

Application filed February 19, 1904, Serial No. 194,419. (No model.)

To all whom it may concern:

Be it known that I, IRA C. CLARK, a citizen of the United States, and a resident of the city of St. Louis and State of Missouri, have 5 invented a new and useful Improvement in Apparel-Attached Pipes, of which the following is a specification.

My invention relates to pipes; and its principal objects are to provide a pipe that may be 10 attached to the wearing-apparel of the smoker when in use; to provide an apparel-attached pipe which may be assembled without the use of solder, rivets, screws, or any fastening means other than that provided by the parts; 15 to provide a pipe having the advantages of a long-stemmed pipe without throwing the weight of the pipe upon the teeth and jaws of the smoker, and other objects hereinafter more fully appearing.

20 My invention consists in the parts and in the arrangements and combinations of parts hereinafter described and claimed.

In the accompanying drawings, forming 25 part of this specification, and wherein like symbols refer to like parts wherever they occur, Figure 1 is a perspective view of my improved pipe. Fig. 2 is a front view showing the stem hung in the clip provided to receive it when not in use. Fig. 3 is a front 30 view with the bowl removed. Fig. 4 is a rear view of the holder of the pipe. Fig. 5 is a fragmentary sectional view of the line 5 5 of Fig. 2. Fig. 6 shows the blank for the cover of the pipe, and Fig. 7 shows the blank 35 for the remainder of the holder.

The use of an ordinary pipe when the smoker is at work is very inconvenient. The weight 40 of the pipe must be sustained by the teeth of the smoker, and it necessarily follows every movement of his head, which results in the frequent spilling of ashes. When not in use, it is placed in the pocket, which it soils, or it is laid down and may be lost, stolen, or used by others. My improved pipe is designed to obviate these objections and others.

45 My improved pipe consists of a holder, a bowl, and a stem. The holder has a body-plate 1, with integral forwardly-extending

resilient bowl-supporting arms 2, a portion of their length being shaped to conform to 50 the shape of the pipe. Substantially in the vertical medial line of the body-plate is an integral projection 3, struck up from the body-plate. Above the bowl-supporting arms 2 clips 4, formed by rebent extensions of the 55 body-plate, are provided. A bowl-cover 5 is supported in these clips 4 by means of a downwardly-turned bifurcated flange 6. This flange slips between the clips 4 and the body-plate. The upper wall of the bifurcation 60 rests upon the projection 3 on the body-plate, and thus limits downward movement. At each side slight projections 7 are struck up in position to rest just below the clips 4 when in position, and thus hold the cover in place. 65 The projections 7 are small enough to be forcibly passed between the clips 4 and the body-plate 1; but it requires a force greater than the weight of the cover to do it. Directly above the projection 2 a small tongue 70 8 is struck up at the rear side of the body-plate. The bar of a safety-pin 9 of ordinary form may be rested upon this tongue and fingers 10 rebent thereover. By this arrangement the pin is secured to the base without 75 the use of solder, rivets, or any fastening means not integral with the base-plate. It is easily removable and, if injured, easily replaceable without the necessity of using any tools. Above the cover is a stem-supporting 80 clip 11, consisting of a resilient tongue struck up from the base-plate.

The holder and cover above described are made from sheet metal and may each be made from an integral piece of metal. The blank 85 for the cover is illustrated in Fig. 6, and the blank for the holder is illustrated in Fig. 7, the portions of the blank from which the various parts are formed being given the same reference-numbers as the parts.

90 The bowl 12 may have any preferred form as to general outline, ornamentation, and the like. It is provided with a groove 13, in which the bowl-supporting arms 2 rest. At the rear side it is provided with a vertical groove 14 95 to receive the projection 3 on the body-plate.

This arrangement insures the maintenance of the preferred position of the bowl—viz., with the stub-stem 15 projecting parallel with this base-plate. This position is preferred, 5 for the stem will then always lie flat upon the breast of the smoker, whether in use or in the clip 11. A stub-stem 15 is secured to the bowl, and to this a flexible stem 16 is connected. In the opposite end of the flexible 10 stem 16 a suitable mouthpiece 17 is inserted.

In use the holder is pinned to the breast of the smoker. The mouthpiece 17 being small and the flexible stem 16 being light, it is as comfortable as a cigarette. The pipe is subjected 15 only to the jars and movements of the smoker's trunk, which are few and not violent, so that the spilling of the ashes is unlikely. The pipe may be used with or without the cover, as preferred. The cover is preferably 20 slightly above the top of the bowl, so as to prevent its being fouled by the raising of the tobacco immediately after it is lighted. When the bowl is removed to be filled, the cover remains on the holder, and thus does not interfere 25 with the filling of the bowl. When not being smoked, the stem may be hung upon the stem-supporting clip 11, as illustrated in Fig. 2, and the pipe simply left in place.

Obviously my device is capable of considerable modification within the scope of my invention, and therefore I do not wish to be limited to the specific construction shown and described.

What I claim as my invention, and desire to 35 secure by Letters Patent, is—

1. An apparel-attached pipe comprising a holder adapted for attachment to wearing-apparel and provided with means to support a pipe-bowl, a bowl, a flexible stem for said 40 bowl, and means to prevent rotation of said bowl when in position on said supporting means.

2. An apparel-attached pipe comprising a holder adapted for attachment to wearing-apparel and provided with forwardly-extending 45 resilient arms and a stem-supporting clip, a bowl having a circumferential groove to receive said arms, and a flexible stem for said bowl.

3. An apparel-attached pipe comprising a

holder adapted for attachment to wearing-apparel and provided with means to support a pipe-bowl and a forwardly-extending projection, a bowl having a recess in position to receive said projection when said bowl is in place 55 on said supporting means, and a flexible stem for said bowl.

4. An apparel-attached pipe comprising a holder adapted for attachment to wearing-apparel and provided with means to support a 60 pipe-bowl, a bowl, a flexible stem for said bowl, and a cover for said bowl removably mounted on said holder.

5. An apparel-attached pipe comprising a bowl, a flexible stem therefor, and a holder 65 comprising a body-plate, integral resilient arms forwardly extending therefrom, a projection substantially in the vertical medial line of said body-plate, and a stem-supporting clip integral with said body-plate. 70

6. A holder comprising a body-plate, an integral tongue projecting rearwardly therefrom, a fastening-pin the bar of which rests upon said tongue, and fingers integral with 75 said body-plate rebent over said bar, whereby the fastening-pin is secured in position solely by parts integral with said base-plate.

7. An apparel-attached pipe comprising a bowl, a flexible stem for said bowl, a holder consisting of a body-plate provided with means to support said bowl, a projection substantially in the vertical medial line, and resilient clips 80 extending toward each other from the sides of said body-plate, and a cover for said bowl having a downwardly-extending bifurcated rear 85 flange provided near its lower edge with projections, said flange adapted to be removably inserted behind said clips with said projections thereon immediately below said clips and the upper wall of the bifurcation resting 90 upon said projection upon said body-plate.

In testimony whereof I have signed my name to this specification, in the presence of two subscribing witnesses, at St. Louis, Missouri, this 16th day of February, 1904.

IRA C. CLARK.

In presence of—

FRED F. REISNER,
J. B. MEGOWN.
